COMBINED RADIO AND TELEVISION CABINET

Freddie Nelson, 1940 Clairmount Ave., Detroit, Mich.

Filed Sept. 4, 1964, Ser. No. 81,602

Term of patent 3½ years

(Cl. D56—4)

The figure is a front perspective view of a combined radio and television cabinet embodying my new design, the back side of the cabinet being plain and the end not illustrated being the same as that illustrated.

I claim:

The ornamental design for a combined radio and television cabinet, substantially as shown and described.
